CLAIM

The ornamental design for a snap-in fitting as shown and described.

DESCRIPTION

FIG. 1 is an isometric view of the snap-in fitting showing our new design;

FIG. 2 is an exploded isometric view thereof;

FIG. 3 is a first side view thereof;

FIG. 4 is a second side view thereof;

FIG. 5 is a top view thereof;

FIG. 6 is a bottom view and thereof;

FIG. 7 is a first end view thereof; and,

FIG. 8 is a second end view thereof.

The broken lines in the drawings depict portions of the snap-in fitting that form no part of the claimed design.
